ATTORNEYS

UNITED STATES PATENT OFFICE.

MARVIN SMITH, OF LAWRENCEVILLE, VIRGINIA.

SPEEDOMETER.

1,211,253.

Specification of Letters Patent.

Patented Jan. 2, 1917.

Application filed September 18, 1916. Serial No. 120,825.

To all whom it may concern:

Be it known that I, MARVIN SMITH, a citizen of the United States, and a resident of Lawrenceville, in the county of Brunswick and State of Virginia, have invented a certain new and useful Improvement in Speedometers, of which the following is a specification.

My invention relates to speedometers, and it consists in the combinations, constructions, and arrangements herein described and claimed.

An object of my invention is to provide a speedometer which works on the centrifugal principle, but which has few parts and which, therefore, is not easily liable to get out of order.

A further object of my invention is to provide a speedometer which is relatively compact in form.

A further object of my invention is to provide a speedometer which responds readily to variations in speed and which accurately registers such variations.

Other objects and advantages will appear in the following specification, and the novel features of the invention will be particularly pointed out in the appended claims.

My invention is illustrated in the accompanying drawings forming part of this application, in which:

Figure 1 is a view partly in section; Fig. 2 is a sectional view at right angles to Fig. 1, and Fig. 3 is a perspective view of one of the operating parts.

In carrying out my invention, I make use of a housing A, see Figs. 1 and 2, for the centrifugal member which operates the speedometer.

The speedometer comprises the shaft 2 upon which is mounted a centrifugal wheel 1, the pivot 1^x of the wheel extending at right angles to the axis of the shaft 2.

The portion of the shaft 2 upon which the wheel is mounted is enlarged as shown at 2^x, and on each side of this portion and surrounding the shaft 2, are springs 3 and 4 respectively. The spring 3 bears against a slidable collar 5 which has a link 6 which pivotally connects the collar with a portion of the wheel. The spring 4 in turn engages a collar 7 which is provided with a link 8 secured to a portion of the wheel 1 on the opposite side of the shaft. Normally the springs 3 and 4 tend to keep the collars 5 and

7 far apart. As the shaft 2 is rotated, the centrifugal force exerted by the wheel tends to pull the collars toward the pivotal point of the wheel against the tension of the springs 3 and 4.

Carried by the collar 7 is an adjustable screw 9, whose inner end extends through a slot 10 in the hollow portion 11 of the shaft 2.

Slidably disposed in the hollow portion 11 is a plunger having a grooved head 12, and a guide member 13. The end of the screw 9 is disposed in the groove in the head 12, so that the shaft 2 may be rotated without rotating the plunger 12. Any longitudinal movement of the screw 9 along the shaft 2, however, will cause a movement of the plunger 12.

Extending from the guide member 13 is an arm 14 which is bent laterally as shown in Fig. 3, the end of this arm bearing a pin 15 arranged to extend through a cam slot 16 in an extension 17 of a sleeve 18 to which a bevel gear 19 is secured. The bevel gear 19 in turn meshes with a bevel gear 20 on the hub 21 of a number wheel 22, this number wheel being observed through a window 23.

When the shaft 2 is stationary, the wheel 1 occupies the position shown in Fig. 3, but when the shaft 2 is in motion the rotation of the shaft will cause the wheel 1 to assume a position more nearly at right angles to the axis of the shaft 2. This will cause the collars 5 and 7 to approach one another. The movement of the collar 7 will cause the movement of the plunger 12 in the hollow portion of the shaft, thus moving the arm 14. The slot 16 is so formed that the movement of the pin 15 along the slot will cause the revolution of the wheel 22 a distance proportional to the speed of revolution of the shaft 2. The form of the cam slot 16 is, of course, found by experiment.

I claim:

1. A speedometer comprising a drive shaft, a centrifugal member pivotally mounted on said drive shaft, a slidable collar mounted on said drive shaft, means pivotally connecting said collar with said centrifugal member, a spring for opposing the movement of the collar, a number wheel, a movable member having a cam groove, means for connecting said movable member with said number wheel and for rotating the

- latter, and a rigid connection having engagement with the slidable collar at one end and being provided with a pin arranged to traverse said cam groove at the other end.
- 5 2. A speedometer comprising a drive shaft, a centrifugal member pivotally mounted on said drive shaft, a slidable collar mounted on said drive shaft, means pivotally connecting said collar with said centrifugal member, a spring for opposing the movement of the collar, a number wheel, said number wheel being provided with a hub having a bevel gear, a second bevel gear arranged to mesh with the first named bevel gear, a sleeve for supporting said bevel gear, an extension through said sleeve provided with a cam groove, a rigid connection having engagement with the collar at one end, and being provided with a pin at the other 10 end arranged to traverse the cam groove.
- 15 3. A speedometer comprising a drive shaft, one end of said drive shaft being hollow, a centrifugal member pivotally mounted on said drive shaft, a slidable col-
- lar carried by the hollow end of the drive shaft, means pivotally connecting said collar with said centrifugal member, a spring for opposing the movement of the collar, said shaft being provided with a longitudinal slot, a screw carried by said collar and arranged to extend through said slot, a plunger having a grooved head disposed within said hollow shaft, the end of the screw entering the grooved head of the plunger, the opposite end of the plunger being provided with a laterally extending arm, a pin carried by the arm, a sleeve mounted for rotation and having a bevel gear secured thereto at one end, an extension carried by the sleeve at the opposite end and being provided with a cam groove arranged to receive the pin on said arm, a number wheel mounted for rotation around its axis, and a bevel gear carried by the number wheel and arranged to be engaged by the first 20 named bevel gear.
- 25 4. A speedometer comprising a drive shaft, one end of said drive shaft being hollow, a centrifugal member pivotally mounted on said drive shaft, a slidable col-
- lar carried by the hollow end of the drive shaft, means pivotally connecting said collar with said centrifugal member, a spring for opposing the movement of the collar, said shaft being provided with a longitudinal slot, a screw carried by said collar and arranged to extend through said slot, a plunger having a grooved head disposed within said hollow shaft, the end of the screw entering the grooved head of the plunger, the opposite end of the plunger being provided with a laterally extending arm, a pin carried by the arm, a sleeve mounted for rotation and having a bevel gear secured thereto at one end, an extension carried by the sleeve at the opposite end and being provided with a cam groove arranged to receive the pin on said arm, a number wheel mounted for rotation around its axis, and a bevel gear carried by the number wheel and arranged to be engaged by the first 30 named bevel gear.
- 35 5. A speedometer comprising a drive shaft, one end of said drive shaft being hollow, a centrifugal member pivotally mounted on said drive shaft, a slidable col-
- lar carried by the hollow end of the drive shaft, means pivotally connecting said collar with said centrifugal member, a spring for opposing the movement of the collar, said shaft being provided with a longitudinal slot, a screw carried by said collar and arranged to extend through said slot, a plunger having a grooved head disposed within said hollow shaft, the end of the screw entering the grooved head of the plunger, the opposite end of the plunger being provided with a laterally extending arm, a pin carried by the arm, a sleeve mounted for rotation and having a bevel gear secured thereto at one end, an extension carried by the sleeve at the opposite end and being provided with a cam groove arranged to receive the pin on said arm, a number wheel mounted for rotation around its axis, and a bevel gear carried by the number wheel and arranged to be engaged by the first 40 named bevel gear.
- 40 6. A speedometer comprising a drive shaft, one end of said drive shaft being hollow, a centrifugal member pivotally mounted on said drive shaft, a slidable col-
- lar carried by the hollow end of the drive shaft, means pivotally connecting said collar with said centrifugal member, a spring for opposing the movement of the collar, said shaft being provided with a longitudinal slot, a screw carried by said collar and arranged to extend through said slot, a plunger having a grooved head disposed within said hollow shaft, the end of the screw entering the grooved head of the plunger, the opposite end of the plunger being provided with a laterally extending arm, a pin carried by the arm, a sleeve mounted for rotation and having a bevel gear secured thereto at one end, an extension carried by the sleeve at the opposite end and being provided with a cam groove arranged to receive the pin on said arm, a number wheel mounted for rotation around its axis, and a bevel gear carried by the number wheel and arranged to be engaged by the first 45 named bevel gear.

MARVIN SMITHEY.
